Inventor:

J. Dohnal

UNITED STATES PATENT OFFICE

JAN DOHNAL, OF DOBRIS, CZECHOSLOVAKIA

SCREW CLAMP

Application filed March 14, 1929, Serial No. 347,120, and in Germany January 31, 1928.

The invention relates to a screw clamp in which the arm that constitutes the bearing for the clamping screw is arranged as a lever, to which an adjustable forked arm, that is 5 provided on the longer branch of the angle rail, is connected by means of a pivot on which the lever with the clamping screw can rotate, the free, upper end of the lever being provided with teeth which prevent the forked 10 arm from slipping on the angle rail when objects are clamped in the device. As it is necessary for certain classes of work to have the screw clamp standing in a vertical position the invention provides for a pin which 15 is passed through the shorter branch of the angle rail and bent downwards on both ends so as to form a foot on which the screw clamp rests when standing in a vertical position.

In the accompanying drawing the invention is illustrated in one form by way of example in which Figure 1 is a side elevation of the screw clamp, Figure 2 a plan view of the same, Figure 3 is a front elevation of the forked and lever arms alone showing the 25 connection between these two parts, and Figure 4 a screw clamp on a smaller scale standing up in a vertical position.

The forked arm *b* is guided on the longer branch of the angle rail *a* and connected with 30 the lever *c* by means of the pivot *d* in such a manner that the lever can be rotated. The clamping screw *e* with the handle *f* on one end and a clamping jaw *g* on the other end is arranged in the lower end of the lever *c* in 35 the usual manner. The clamping plate *h* is provided on the shorter branch of the angle rail *a* opposite the clamping jaw *g*.

When any object is to be clamped between 40 the clamping plate and the clamping jaw in the screw clamp, the lever *c* rotates in the direction indicated by the arrow *x* on the pivot *d* until the clamping action is attained by means of turning the clamping screw the lever *c* then takes up the pressure generated 45 and transfers it, by rotating in the direction indicated by the arrow *y*, as a counter pressure by means of the teeth on its upper end onto the rail *a*, so that the lever becomes firmly 50 positioned and the forked arm cannot slip on the angle rail.

The pin *i* which is firmly located in the shorter branch of the angle rail, is bent downward on both ends so as to form a foot upon which the screw clamp may stand in the position as shown in Figure 4. The single parts 55 of the device are to be preferably made of hardened steel, which is particularly advantageous for the surfaces between the lever *c* and the angle rail against premature wearing 60 away of the material.

I claim:

1. A screw clamp, comprising, in combination, a lever arm connected so as to be rotatable, with an adjustable forked arm provided on the longer branch of the angle rail of a screw clamp, the free, upper end of the said lever being provided with teeth adapted to engage against the inner surface of said longer angle rail branch and to hold said adjustable forked arm firmly located in any given position on said rail branch, said lever arm being provided with a clamping screw having a handle and a clamping jaw and means for holding said screw clamp standing 70 in a vertical position, substantially as set forth.

2. A screw clamp, comprising, in combination, a lever arm connected, so as to be rotatable, with an adjustable forked arm provided on the longer branch of the angle rail of a screw clamp, the free, upper end of said lever being provided with teeth adapted to engage against the inner surface of said longer angle rail branch and to hold said adjustable forked arm firmly located in any given position on the said rail branch, said lever arm being provided with a clamping screw having a handle and a clamping jaw, a pin through the shorter branch of said angle rail, said pin being bent down on both ends to form a foot adapted to hold said screw clamp standing in 80 a vertical position, substantially as described.

JAN DOHNAL.
